UNITED STATES PATENT OFFICE.

WILLIAM ALBERT WHITE, OF NEW YORK, N. Y.

FURNACE-FRONT.

1,082,835.

Specification of Letters Patent. Patented Dec. 30, 1913.

Application filed November 4, 1912. Serial No. 729,186.

To all whom it may concern:

Be it known that I, WILLIAM ALBERT WHITE, a citizen of the United States, and resident of the borough of Manhattan, in the city, county, and State of New York, have invented certain new and useful Improvements in Furnace-Fronts, of which the following is a specification.

The invention relates to furnaces wherein liquid hydrocarbon is employed as fuel, and my improvement has particular reference to the furnace front, at which the oil and air are admitted, the leading characteristic distinguishing my said improvement residing in certain means whereby the atomized oil introduced into the furnace by the burner, receives an admixture of air in manner to promote complete combustion in all parts of the furnace.

Hitherto, in oil furnaces of the type in question practice has shown that at the forward end of the furnace from which the fuel is admitted, especially in the larger radii thereof or parts distant from the burner, combustion is less thorough than in the more rearward portions of the furnace interior, and it is the purpose of my improvement to cause a portion of the entering fuel, having commingled and burning therewith an ample air supply, to be directed forwardly and radially, and thus to set up and maintain in the forward portion of the furnace a temperature equal to that obtaining in the more rearward furnace portions, thereby establishing a higher average of efficiency for the entire furnace, tending to eliminate all smoke.

The instrumentalities employed by me in attaining the aforesaid result, include a perforated tube surrounding the burner tube over an intervening annular space, the perforations admitting air between said tubes for issuance about the burner nozzle; also, a flaring cone slidable upon said perforated tube, acting in conjunction with a surrounding constricted air supply tube, to deflect certain portions of the entering air, and to set up a swirling action in this air; whereby, as it mixes with the atomized fuel from the burner, a part of the burning mixture is caused to turn into the forward portion of the furnace, this action not detracting from the penetration of the more rearward furnace portions of the bulk of the burning mixture.

In the drawing: Figure 1 is a side sec-

tional elevation of the front portion of a furnace, containing my improvement; Fig. 2 is a rear elevation of the same; Fig. 3 is an enlarged detail side sectional view of the fuel and air entering devices. Fig. 4 is a detail in section showing the front arranged for natural draft. Fig. 5 is a perspective view of the air jacket for the burner; and Fig. 6 is a section on line 6--6 of Fig. 5.

In said figures the letter *a* indicates the shell of an oil burning furnace, of which the front portion is constructed according to my invention. Said front portion is composed in part of the inner circular furnace or heat plate *b*, an outer, circular plate, as *c*, being separated from plate *b* by an intervening space, which is divided into a number of centering passages *d* by partitions *d'* and short, intermediate partitions *d''*. An air inlet, as *e*, is provided near the periphery of plate *c*, and the air received thereat, in passing to the center, is heated in its passage by impingement against the undulations or angular surfaces of partitions *d'*. Said air inlet *e* extends about the periphery of plate *c*, and is inclosed by an annular air box *e'* to which air under pressure may be supplied, as through pipe *e''*, when it is desired to employ forced draft. When natural draft is employed the annular wall *b'* of the furnace front is provided with slides, as *e''*, which may be moved in or out to regulate the air admission. An oil burner, as *f*, is supported centrally and axially through plate *c*, as by a spider or housing *g*, which may be bolted to said plate *c*; the burner nozzle projecting toward the furnace interior, through a central opening formed in plate *b*. Projecting inwardly from plate *b*, in concentric relation with the oil burner *f*, is an air outlet or supply tube *h*, said outlet extending inwardly beyond the burner nozzle, and having a constricted or Venturi-like neck portion *h'*, to increase the velocity of air inflow at the point of initial combustion.

An approximately cone-faced valve, as *i*, is mounted concentrically about and adapted to slide longitudinally about the burner tube, to increase or decrease the size of the air passage allowed through outlet *h*, and thereby regulate the quantity of preheated air for combustion supplied to the burner. The valve *i* may be hollow, and have openings *i'* in its cone-face to permit air to circulate about the burner tube. Said valve may also have an observation opening or

tube j^2 therethrough. Extension rods, as j , extending from the rear of valve i , pass outwardly through holes provided therefor in spider g , and may thereby be manipulated to operate the valve.

Obviously, the supply tube h may be held in position in any suitable manner. As here shown it has an annular flange h^2 , by which it is bolted to a ring h^3 , held against the outer surface of plate b , lying within a recess b^2 therein, whereby it may be easily removed. The spider g has a flange g^2 through which it is held in engagement with the plate c by pivotal catches as g^2 . Connections, as the legs h^4 , connect spider g with ring h^3 . In this manner the spider g , carrying the burner, valve and supply tube may be easily adjusted and secured in place, or removed. Surrounding burner f is a larger tube k , which may be integral with spider g , as seen, or a separate member. The clearance l between tube k and burner f is intended as a space or passage for the travel of air which is induced to enter said space through orifices k' provided for that purpose in tube k to cool the burner tube f . Said orifices k' are inclined forwardly and tangentially through the wall of tube k , whereby the air enters the aforesaid space or passage in the form of jets, and issues from said passage as a whirling mass. The valve i has its sliding bearings upon this tube k , which is really an air jacket, since it supplies a layer of cooling air directly against said burner.

Fitting slidably upon tube k , at its forward end, is an outwardly flaring cone-like deflector, as m , having a collar or flange n , by which it is slidably supported. The outer periphery of deflector m is normally in about the central transverse plane of air supply tube h , but the axial position of said deflector may be varied, as by manipulating the rods o which extend therefrom and pass out through the spider, for that purpose.

In considering the action of the atomized fuel and air issuing from their respective passages into the furnace, we find the following condition: The burner being of the type that imparts a swirling, spreading motion to the atomized fuel, causes the fuel to be thus projected from its nozzle, while within air supply tube h . The regulated quantity of air, entering from the heating passages d , strikes against tube k and deflector m ; and, while some of this air passes through orifices k' , and issues as a hollow column of air, concentrically upon the inner radial surface of the atomized fuel, other quotas of the entering air impinge against the rear surface of deflector m , and are given a rolling motion which causes this air, as it strikes against and mingle with the outer radial portions of the fuel mass, to carry the burning mixture back to the

forward portion of the furnace, thus performing an important function of this invention.

The air supplied to the orifices k' , while it is heated, is still of a temperature considerably below that of the interior of the furnace, and thus has a cooling effect on the burner nozzle, which is partly exposed to the furnace heat.

Longitudinal adjustment of deflector m permits a variation in degree of its aforesaid influence upon the passing air, to suit all practical conditions of operation.

I claim:

1. A furnace front, a burner tube entered therein, a perforated cooling jacket spaced from and surrounding said burner tube, and a main air supply means surrounding said jacket, said perforated cooling jacket receiving air from said main air supply for impingement upon the burner tube, and for issue about the burner nozzle.

2. A furnace front, a burner tube entered therein, a cooling jacket surrounding the burner tube and spaced therefrom to form an annular air passage, and a main air supply means surrounding the cooling jacket, said jacket having perforations to receive air from said main air supply for impingement upon said burner tube, together with a cone-like, imperforate, outwardly flaring deflector surrounding the burner nozzle.

3. A furnace front, a burner tube entered therein, a perforated jacket surrounding said burner tube and providing an intermediate air passage, and an axially adjustable deflector surrounding the burner nozzle.

4. A furnace front, a burner entered therein, a perforated jacket for said burner providing an intermediate air passage, an axially adjustable deflector surrounding the burner nozzle, and a constricted air supply tube surrounding said deflector.

5. A furnace front, a burner entered therein, a perforated jacket for said burner providing an intermediate air passage, an axially adjustable deflector surrounding the burner nozzle, a constricted air supply tube surrounding said deflector, and a cone-like valve axially adjustable with respect to said air supply tube.

6. A furnace front, centering air heating passages therein, a peripheral inlet to said passages, an annular air box inclosing said inlet and means for introducing air under pressure to said air box.

7. A furnace front, a burner tube entered therein, and a jacket surrounding and being co-extensive with said burner tube and spaced therefrom to form an intermediate, annular air passage, to deliver a hollow column of air at the burner nozzle; said jacket having a series of tangential, forwardly di-

rected perforations to cause air jets to impinge upon the burner tube and supply said air passage.

8. A furnace front, a burner tube entered therein, and a jacket surrounding and being co-extensive with said burner tube and spaced therefrom to form an intermediate, annular air passage, said jacket being closed at its rear end and having a series of tangential, forwardly directed perforations to cause air jets to impinge upon the surface

of said burner tube, and deliver a swirling hollow column of air about the burner nozzle.

Signed at the borough of Manhattan in 15 the city, county and State of New York this 30th day of October A. D. 1912.

WILLIAM ALBERT WHITE.
